INVENTOR:

David H. Bucher,

BY

Arthur H. Ewald,
ATTORNEY.

UNITED STATES PATENT OFFICE.

DAVID H. BUCHER, OF LOUISVILLE, KENTUCKY.

COLLAPSIBLE PAIL.

1,353,627.

Specification of Letters Patent. Patented Sept. 21, 1920.

Application filed May 29, 1920. Serial No. 385,323.

To all whom it may concern:

Be it known that I, DAVID H. BUCHER, a citizen of the United States, and resident of Louisville, in the county of Jefferson and 5 State of Kentucky, have invented certain new and useful Improvements in Collapsible Pails, of which the following is a full, clear, and exact description, reference being had to the accompanying drawings, 10 forming a part of this specification.

My invention relates to collapsible pails and has particular reference to the provision of a device of this character suitable for use in the filling of automobile radiators.

15 It frequently happens during travel that the operator of a motor vehicle is required to refill the radiator at times when no ordinary vessel suitable for the purpose is available. The principal object of the present 20 invention is to provide a collapsible pail suitable for convenient storage which is adapted for the purpose designated.

Under the general conditions outlined furthermore it is frequently necessary that 25 water be taken from shallow streams, and under such circumstances ordinary vessels are poorly adapted for drawing a sufficient supply. A further object of this invention is therefore to provide a collapsible pail 30 suitable for use in drawing water from shallow deposits.

Further objects of the invention will appear from the following detailed description thereof.

35 In the drawings:

Figure 1 is a perspective of my invention as used in the filling of an automobile radiator;

Figs. 2 and 3 are side elevations of the 40 pail;

Fig. 4 is a central vertical section thereof.

The numerals 1 and 2 indicate respectively two pieces of suitable flexible material, such as oiled or rubber coated cloth or 45 leather. The pieces 1 and 2 are stitched together at the edges as shown at 3 in Figs. 2 and 3 and together form a flat vessel or pail. The piece 1 is longer than the piece 2 and provides an end strip or flap 4 which extends above the upper or free edge of the piece 2. Along the free edge of the flap 4 is placed a stiffening member 5, which may be of wood or metal and is secured to the flap by means of rivets, nails or in any other 50 suitable manner. Secured to the outer sides

of the flap 4 and the upper portion of the piece 2 is a flexible bail or strap 6 which serves as a handle for carrying and handling the pail. The other end or bottom of the pail is provided with a strap or loop 7, 60 suitable for lifting the bottom of the pail while emptying the same into the radiator or other receptacle. Mounted in the piece 1 near the top of the pail is a spout or pouring tube 8, the same being of metal or other 65 suitable construction.

From the foregoing description the nature of the present invention will be apparent to those skilled in the art. As will be seen, a pail constructed of the flexible 70 pieces 1 and 2 may be conveniently rolled or folded for storage purposes. Being flat the pail is adapted to be inserted into, and to scoop up water from shallow places. When filled the pail may be carried by 75 means of the flexible handle 6 without leakage through the spout 8 for the reason that said spout is near the top of the pail. In order to pour from the pail, for instance into the filling tube 9 of an automobile radiator, the spout 8 is inserted therein and the bottom of the pail lifted by means of the strap 7. The operator still maintaining hold upon the bail 6, the flap 4 of the pail is 80 folded upwardly and forms a cover for the 85 pail to prevent leakage during the operation. It will be obvious that by reason of the construction herein described it is possible to employ a spout or tube in the bucket without the necessity of providing a valve 90 therefor.

Having thus fully described my invention, what I claim as new and desire to secure by Letters Patent, is:

1. In a collapsible pail in combination 95 with the body of the pail, a pouring spout located in the upper portion of said body, a flap adapted to form a closure for the mouth of the pail, and a stiffening strip along the free edge of said flap.

2. In a collapsible pail in combination 100 with the body of the pail, a pouring spout located in the upper portion of said body, a flap adapted to form a closure for the mouth of the pail, and a flexible bail secured to said flap and the opposite side of the pail.

3. In a collapsible pail in combination 105 with the body of the pail, a pouring spout located in the upper portion of said body, a flap adapted to form a closure for the mouth 130

of the pail, a stiffening strip along the free edge of said flap, and a flexible bail secured to said flap and the opposite side of the pail.

5. 4. In a collapsible pail in combination with the body of the pail, a pouring spout located in the upper portion of said body, a flap adapted to form a closure for the mouth of the pail, and a loop secured to the bottom of said pail.

5. In a collapsible pail in combination with the body of the pail, a pouring spout located in the upper portion of said body, a flap adapted to form a closure for the mouth 15 of the pail, a stiffening strip along the free edge of said flap, and a loop secured to the bottom of said pail.

6. In a collapsible pail in combination with the body of the pail, a pouring spout located in the upper portion of said body, a flap adapted to form a closure for the mouth 20 of the pail, a flexible bail secured to said

flap and the opposite side of the pail, and a loop secured to the bottom of said pail.

7. In a collapsible pail in combination 25 with the body of the pail, a pouring spout located in the upper portion of said body, a flap adapted to form a closure for the mouth of the pail, a stiffening strip along 30 the free edge of said flap, a flexible bail secured to said flap and the opposite side of the pail, and a loop secured to the bottom of said pail.

8. A collapsible pail comprising two pieces of flexible material secured together 35 at their edges to form a flat pail having one side open, one of said pieces of material being longer than the other so as to extend beyond the latter along the open side to form a free flap for the temporary closure 40 of the pail, and a pouring spout located in the longer piece of material near the open side of the pail.

DAVID H. BUCHER.
